(57) **CLAIM**

The ornamental design for an earphone case and earphones as shown and described.

DESCRIPTION

FIG. 1 is a perspective view of the earphone case and earphones showing my new design;

FIG. 2 is a front elevational view of the earphone case thereof, in a closed position, shown separately for clarity of illustration;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof;

FIG. 9 is a second perspective view thereof;

FIG. 10 is a third perspective view thereof;

FIG. 11 is a front elevational view of the left earphone thereof, shown separately for clarity of illustration;

FIG. 12 is a rear elevational view thereof;

FIG. 13 is a left side view thereof;

FIG. 14 is a right side view thereof;

FIG. 15 is a top plan view thereof;

FIG. 16 is a bottom plan view thereof;

FIG. 17 is a perspective view thereof;

FIG. 18 is a front elevational view of the right earphone thereof, shown separately for clarity of illustration;

FIG. 19 is a rear elevational view thereof;

FIG. 20 is a left side view thereof;

FIG. 21 is a right side view thereof;

FIG. 22 is a top plan view thereof;

FIG. 23 is a bottom plan view thereof; and,

FIG. 24 is a perspective view thereof.

The broken lines depict portions of the earphone case and earphones that forms no part of the claimed design.
